UNITED STATES PATENT OFFICE.

JOHN M. WEISS, OF NEW YORK, N. Y., AND CHARLES R. DOWNS, OF CLIFFSIDE, NEW JERSEY, ASSIGNORS TO THE BARRETT COMPANY, A CORPORATION OF NEW JERSEY.

PRODUCTION OF MALEIC ACID.

1,377,534.

Specification of Letters Patent. Patented May 10, 1921.

No Drawing.

Application filed June 18, 1920. Serial No. 389,827.

To all whom it may concern:

Be it known that we, JOHN M. WEISS and CHARLES R. DOWNS, citizens of the United States, residing at New York city and Cliff-side, New Jersey, respectively, in the counties of (1) New York, (2) Bergen, and State of (1) New York, (2) New Jersey, have invented certain new and useful Improvements in the Production of Maleic Acid, of which 10 the following is a specification.

This invention relates to the catalytic oxidation of aromatic hydrocarbons and to the production of products of partial oxidation therefrom. It relates more particularly to 15 the catalytic oxidation of toluene and the production of maleic acid therefrom, but is not intended to be confined solely to this material. The invention comprises a method of effecting the partial or selective oxidation 20 of an aromatic hydrocarbon that contains at least one benzene ring in such a manner that the benzene ring will be split. In practising this invention, the hydrocarbon is subjected to oxidation by oxygen either alone or 25 mixed with other gases, or by means of an oxygen containing gas, in the presence of a catalyst.

It has heretofore been known that an aromatic hydrocarbon, such as toluene, for example, could be oxidized so that the oxygen enters into the side chain to produce benzaldehyde and benzoic acid. Other aromatic hydrocarbons containing side chains are amenable to oxidation by which the side 35 chains are oxidized. It is also known that aromatic hydrocarbons such as toluene may be oxidized by combustion, much the same as other combustible hydrocarbons, with the formation of carbon dioxide and water.

40 The present invention is based upon the discovery that by subjecting certain hydrocarbons containing a benzene ring or nucleus to oxidation, in the presence of an appropriate catalyst and at an appropriate temperature, the ring or nucleus may be broken and a selective or partial oxidation thereof be made to take place short of complete oxidation or combustion with the consequent formation of products of partial oxidation, 45 one or more of these products being of the aliphatic or straight chain series.

The invention will be described in connection with the following specific example, 50 illustrative thereof, but it is to be understood that we do not limit ourselves to the

details of this example, which is given to render the invention clearly understood. A mixture of toluene in the vapor phase and an oxygen containing gas such as air, is passed through a container which contains 60 vanadium oxid. The vanadium oxid may be distributed upon pumice or any other suitable catalyst carrier, and should be heated to a temperature of 400° C. or above, and may be as high as 550° C. or higher. 65

It is already known that if toluene is passed into contact with vanadium oxid as a catalyst at a temperature between 200° C. and 400° C., the side chain will be oxidized to produce benzaldehyde and benzoic acid. 70 We have found that the production of maleic acid begins in appreciable amounts when temperature of the vanadium oxid catalyst is about 400° C. with a diminution in the amount of production of benzaldehyde and 75 benzoic acid, but that when the temperature is raised much above 550° C. the complete oxidation of the materials takes place to an objectionable extent with a consequent waste of the hydrocarbon that is being oxidized. 80

We have found in practising this invention that the proportions of oxygen and toluene can be varied over wide limits, an increased proportion of oxygen causing a corresponding increase in the oxidizing effect 85 when other conditions are maintained constant. A convenient proportion with a catalyst temperature of about 430° C. using vanadium oxid as a catalyst and maintaining the time of contact between reaction gases and catalyst for about one-quarter of a second, has been found to be about 6 parts of air by weight to one part of toluene. The statement of temperatures throughout the specification and claims is intended to refer to the temperatures of the catalyst mass. 90

The relative proportions of the products present in the exit gases can be made to vary by varying the conditions of operation. If a considerable excess of toluene is used over and above that which is oxidized, some of the toluene will be converted into benzaldehyde and benzoic acid, respectively, if the temperature is not too high, and the remaining toluene will pass through the reaction chamber practically unchanged and the reaction gases will be correspondingly diluted by the excess toluene present during the reaction. The nitrogen of the air will have 105 110

a correspondingly diluent effect. Any steam, if present, will similarly have a diluent effect, for example, in case moist air, instead of dry air, is used in the process of the 5 above specific example. Since water is always practically formed as a product, some steam is present as a consequence.

The conditions of operation may be widely varied and a variation in one condition of 10 operation will have an effect which may be counterbalanced or partially counterbalanced by varying another condition or conditions of operation. Among these conditions may be mentioned the temperature 15 and pressure at which the reaction is carried out; the time of contact of the reactive gases with the catalyst; the proportion of catalyst to the reacting gases; the proportion of toluene to oxygen and diluent gases, 20 etc. It will be understood that the oxidation takes place more readily with some catalysts than with others, that it is more rapid with higher temperatures, that it progresses further with an increase in the 25 time of contact, etc. However, the specific conditions above enumerated have been found to give good results though the invention is not restricted to the particular conditions enumerated, except that the range of 30 temperature should be restricted from about 400° C. to about 550° C. for all conditions of operation which we have tried. The formation of maleic acid in the manner above described involves the breaking of the 35 benzene-ring or nucleus in a characteristic manner, that is, the breaking of this nucleus or ring in such a way that there remain four carbon atoms united to each other in the form of the straight chain or aliphatic compound (maleic acid), which represents a 40 stage of partial oxidation of the aromatic hydrocarbon. It is to be understood that the compound maleic anhydrid is included in the term "maleic acid". Fumaric acid 45 seems to be formed to some extent, and is occasionally found among the products of reaction.

After the products of reaction emerge 50 from the reaction chamber, the maleic acid may be separated therefrom in any convenient way, as, for example, by dissolving the same in water, after which the other products may be separated from each other, if desired, and, the unreacted toluene again 55 passed through the reaction chamber for a further oxidizing treatment. It is not absolutely necessary to separate the benzaldehyde or benzoic acid if present, but these materials may be passed together with the 60 unreacted toluene through the reaction chamber, whereupon they become further oxidized together with more of the toluene to produce additional maleic acid.

It will often be found, however, in the 65 practice of this process that benzaldehyde

and benzoic acid will usually be formed simultaneously with the formation of maleic acid even at temperature considerably above 400° C. and will be present in the reaction products in appreciable quantities. These 70 products can be readily separated from each other, for example, by first condensing the materials after they emerge from the reaction chamber, then leaching with water to remove the maleic acid, treating with sodium carbonate to remove benzoic acid, and finally distilling the residual benzaldehyde and excess toluol.

While the invention has been particularly described in connection with the partial or 80 selective oxidation of toluene, it includes the partial or selective oxidation of other aromatic hydrocarbons which contain at least one benzene ring or nucleus with one or more side chains and substitution products of these hydrocarbons. It is essential in this invention that the benzene ring or nucleus be split so that one or more products are obtained that belong to the straight chain or aliphatic series of compounds. As 85 examples, naphthalene can be oxidized similarly to give phthalic anhydrid, naphthoquinone and maleic acid, anthracene to give anthraquinone and maleic acid. Similarly, xylene, methyl naphthalene, fluorene, ace- 90 naphthene, etc., will give maleic acid as a product of extended oxidation.

We claim:

1. The process of producing maleic acid, benzaldehyde, and benzoic acid, which comprises oxidizing toluene in the vapor phase with an oxygen containing gas in the presence of vanadium oxid as a catalyst at a temperature between 400° C. and 550° C.

2. The process of producing benzaldehyde, 105 benzoic acid and maleic acid which comprises passing toluene and an oxygen containing gas into contact with vanadium oxid, said oxid being maintained during the reaction at a temperature of approximately 110 430° C.

3. The process of producing benzaldehyde, 115 benzoic acid and maleic acid which comprises passing toluene and an oxygen containing gas into contact with vanadium oxid, said oxid being maintained at a temperature of approximately 430° C., and separating the benzaldehyde, benzoic acid and maleic acid from each other.

4. The process which comprises passing 120 toluene and an oxygen containing gas into contact with vanadium oxid at a temperature between 400° C. and 550° C., and recovering maleic acid from the products of reaction.

5. The process which comprises oxidizing 125 toluene in the vapor phase with an oxygen containing gas in the presence of vanadium oxid as a catalyst at a temperature between 400° C. and 550° C., separating maleic acid, 130

benzaldehyde, and benzoic acid from any unchanged toluene and returning the toluene for a similar oxidizing treatment.

6. The process of producing maleic acid which comprises passing a hydrocarbon containing a single benzenoid ring or nucleus and a substituent group together with an oxygen containing gas into contact with a catalyst at a temperature between 400° C. and 550° C.

7. The process of producing maleic acid which comprises passing a hydrocarbon containing at least one benzenoid ring or nucleus and a substituent group together with an oxygen containing gas into contact with vanadium oxid as a catalyst at a temperature between 400° C. and 550° C.

8. The process of producing maleic acid

which comprises passing a hydrocarbon containing a single benzenoid ring or nucleus 20 and a substituent group together with an oxygen containing gas into contact with vanadium oxid as a catalyst at a temperature between 400° C. and 550° C.

9. The process of producing maleic acid 25 which comprises passing a hydrocarbon containing at least one benzenoid ring or nucleus and a substituent group together with an oxygen containing gas into contact with a catalyst at a temperature between 400° C. 30 and 550° C.

In testimony whereof we affix our signatures.

JOHN M. WEISS.

CHARLES R. DOWNS.
